By Tom Walker Attorney

UNITED STATES PATENT OFFICE

2,599,004

ANTICREEPER RAILWAY RAIL

Vergil M. Lutz, Springfield, Ohio

Application November 8, 1947, Serial No. 784,846

7 Claims. (Cl. 238—315)

1

This invention relates to railway rail anchoring apparatus, and more particularly to anti-creeping devices, and the method of manufacture thereof.

Anti-creeping devices have heretofore been known and used. They are anchor-like elements which are applied to railway rails to restrain longitudinal shifting of the rails occasioned by the thrust and vibration set up by passing rolling stock. In railroad terminology this longitudinal shifting of the rails is known as "creeping," and devices provided to inhibit such motion are called "anti-creepers."

The development of anti-creepers has been intensively pursued to the end that these devices may more efficiently perform their function, may be used in fewer number, be easier of installation, and be more simply and readily manufactured.

The object of the invention is to improve the construction as well as the method of manufacture and the mode of operation of anti-creepers for railway rails, whereby they may not only be economically manufactured, but will be efficient in use, easily installed and unlikely to get out of repair.

It is thought that the anti-creepers embodied in the apparatus of the present invention incorporates these sought after features to a degree greater than any in the prior art, and it is the general object of the invention to obtain a device so characterized.

More specifically, it is an object of the invention to provide a more substantial mounting for the anti-creepers, and one which makes possible a reduction in the number of such devices required for a given length of rail, by making the anti-creepers in effect a part of the rail bed plate mounted directly upon the tie. In the past it has been the practice to mount the anti-creepers between adjacent ties and in abutment with one of them, a pair of the devices being required to resist rail motion in opposite directions.

Another object of the invention is to make the anti-creepers from one-piece spring metal bar stock, so forming the bar as to provide means at both ends of the device for engagement with opposite side edges of the rail flange, at least one of the means constituting jaws for clamping engagement with the flange.

A further object of the invention is to impart a set twist to the jaw portion of the anti-creepers device in such a way as to resolve the clamping pressure thereof into lateral and opposed longitudinal thrust components.

Still another object of the invention is to impose a positive restraint upon the rail by forming

2

the bar of which the anti-creepers is made of stock which is approximately square in cross-section, the corners of the bar being presented for contact with the rail flange in response to the twisting of the jaws and such corners cutting into and becoming embedded in the rail flange under the clamping pressure.

A still further object of the invention is to obtain a method of making and forming the anti-creepers device which may be used quickly and easily to attain the structure above described.

With the above primary and other incidental objects in view as will more fully appear in the specification, the invention intended to be protected by Letters Patent consists of the features and method of construction, the parts and combinations thereof, and the mode of operation and use, or their equivalents, as hereinafter described or illustrated in the accompanying drawings.

20 In the accompanying drawings, wherein is illustrated the preferred but obviously not necessarily the only form of embodiment of the invention:

Fig. 1 is a perspective view of the anchoring apparatus of the invention installed in cooperative relation with a railway rail and tie;

Fig. 2 is a detail plan view of the anti-creepers device;

Fig. 3 is a view of a railway rail in cross-section, showing the anti-creepers and bed plate assembly in side elevation applied thereto;

Fig. 4 is a detail view showing the jaws of the anti-creepers device in cross-section clamped together for application to a rail flange; and

35 Fig. 5 is a view similar to Fig. 4, showing the jaws released and in clamping engagement with the rail flange.

Like parts are indicated by similar characters of reference throughout the several views.

Referring to the drawings, a railway rail is indicated at 10, having the usual base flange 11. The base flange 11 of the rail rests on a bed plate 12, in turn secured by spikes 13 to a tie 14.

The bed plate 12 is a metal plate having an elevated land or track portion 15 on which the rail flange 11 seats. Defining one side edge of the track portion 15 of the plate 12 is a longitudinal shoulder 16 against which the flange 11 abuts. The spikes 13 have heads overlapping the side edges of the flange 11 and so act in conjunction with the shoulder 16 on the bed plate to hold the rail firmly upon the tie 14 and assist in inhibiting longitudinal creeping of the rail.

Positively acting means serving the latter function is provided in the form of an anchor or anti-

creeper device 17, positioned within an opening 18 in the bed plate 12. Together, the device 17 and bed plate 12 comprise rail anchoring apparatus. The opening 18 extends transversely beneath the rail flange 11 with the ends thereof lying beyond the side edges of track portion 15. The device 17, as shown in Fig. 2, is of integral one-piece construction being fabricated from spring metal bar stock which when viewed in cross-section has a substantially square shape. In forming the device, the bar is bent about its approximate mid-point to define a pair of elongated parallel fingers 19. The closed or base end of the device is upturned in the form of a lip 21 engageable with one side edge of the rail flange 11. The opposite or free ends of the fingers 19 are reversely bent upon the fingers and in spaced relation thereto and in parallel relation to each other to define a pair of prongs 22. At a point adjacent their ends the prongs 22 are bent to an inclined angle in conformance with the slope of the rail flange 11. The prongs 22 are in predetermined spaced relation to the fingers 19 to form with the fingers, jaws receiving the side edge of the flange opposite that engaged by lip 21. The spacing between the prongs 22 and fingers 19 is such as to cause the jaws yieldingly to separate when applied to the flange, and when installed, to exert a clamping pressure thereon.

The fingers 19 of the device 17 are arranged in contacting relation to the side walls of the openings 18 and are so held against lateral movement relative to the bed plate 12. As a final step in forming of the device 17, the prongs 22 are spread or sprung apart to impart a set twist thereto and to the underlying portions of the fingers 19. In this step of the method the base or closed end of the fingers 19 and portions outward thereof are held or clamped against movement. The spreading or springing of the prongs 22 is continued until corners or angle portions thereof and of the underlying fingers 19 are presented for contact with the rail flange. As shown in Fig. 5, the relative positions of the prongs and fingers accordingly are such that the outside lower corners of the prongs become contact points, while the inside upper corners of the fingers 19 become contact points, the latter being within or intermediate the relatively wider spacing of the former. Further, the arrangement is such that the angular portions of the prongs and fingers may cut into and become embedded in the surface of the rail flange positively to restrain longitudinal motion thereof. One prong 22 and the finger 19 associated with the other prong 22 complement one another in resisting motion of the rail in one direction, while the other prong and the finger associated with the first prong cooperate in resisting longitudinal motion of the rail in the opposite direction.

In assembling the rail anchoring apparatus, the anti-creeper device 17 may be placed within the opening 18 of the bed plate 12 and the plate then placed on a tie 14 and slipped beneath a rail 10, following which the spikes 13 are driven securely to fasten the plate to the tie. The anti-creeper device 17 is engaged with the rail flange 11 as a part of this motion by placing the prongs 22 on the upper side of one edge of the flange, the installation being completed, if necessary, by driving the device longitudinally to permit the lip 21 to snap into place in engagement with the opposite side edge of the flange. By reason of the angular twist imparted to the jaws of the device in the manufacture thereof, it is more easily in-

stalled by applying a clamping tool to the prongs 22 and squeezing them from their sprung position to a parallel relation as indicated in Fig. 4. The increased spacing so afforded between the prongs and the fingers thus permits easy application of the device to the rail flange. When fully installed with the lip 21 in engagement with the far edge of the flange, the prongs 22 may be released, whereupon they will resume or attempt to resume their original sprung position, and in so doing engage the flange 11 in the manner indicated in Fig. 5.

It will be noted that by reason of the set twist imparted to the prongs 22, the inherent clamping pressure of the jaws upon the flange is resolved into lateral and opposed longitudinal thrusts effectively inhibiting creeping of the rail. Continued use will not loosen the grip of the device 17 since vibration and attempted creeping of the rail merely serve to cause the jaws to cut more deeply into the flange. It is to be further noted in connection with the anchoring apparatus that a single assembly is effective to prevent endwise movement of the rail in either direction. Accordingly, use of the anti-creeper in pairs is unnecessary.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention I claim:

1. An anti-creeper for railway rails, comprising a one-piece length of spring metal having an angular shape in cross-section, said length of metal being bent at approximately its medial point to form a pair of substantially parallel fingers, the ends of said fingers being bent back upon themselves in spaced relation to the fingers and in parallel relation to each other and said ends being spread apart in a manner to impart a set twist to the overlapping portions of said fingers and the ends thereof causing each to present to the other oppositely disposed angle portions.

2. A device according to claim 1, characterized in that the closed end of said device, or the bent portion representing the base of said fingers, is formed with an upturned lip, said lip and the jaws formed by said fingers and the turned over ends of said fingers being engageable with the opposite side edges of a rail flange.

3. An anti-creeper device for railway rails having a base flange, comprising a one-piece length of spring metal having an angular shape in cross-section, said length of metal being bent at approximately its mid-point to form a pair of substantially parallel fingers, the ends of said fingers being bent back upon themselves in parallel relation to each other to form of said

fingers and said bent over ends jaws respectively engageable with the underside and the upper side of a rail flange along one edge thereof, the ends of said fingers and the portions of said fingers overlapped by said ends having a set twist presenting angle portions thereof for contact with the rail flange.

4. An anti-creeper device for railway rails having a base flange, comprising a one-piece length of spring metal having an angular shape in cross-section, said length of metal being bent at approximately its mid-point to form a pair of substantially parallel fingers, the ends of said fingers being bent back upon themselves in parallel relation to each other to form of said fingers and said bent over ends jaws respectively engageable with the underside and the upper side of a rail flange along one edge thereof, said fingers extending along the underside of the rail flange and terminating at their base ends in an upturned lip engageable with the opposite edge of the rail flange, and a set twist in the portions forming said jaws to present angle portions thereof for contact with the rail flange.

5. An anti-creeper device for railway rails having a base flange, comprising a bar of spring metal bent at approximately its mid-point to form two parallel lengths, the ends of said bar being adjacent one another and reversely bent upon themselves and in parallel relation to each other to form jaws to receive one side edge of the rail flange, and said bar ends being sprung apart by opposed torsional twisting of said parallel lengths in such manner that when clamped together and applied to the rail flange said ends when released exert in conjunction with the underlying bar lengths a clamping pressure upon the rail flange, said bar having an angular shape in cross section, the springing of said bar ends imparting a twist thereto and to the underlying bar lengths causing such portions of the bar to present angle surfaces for contact with the rail flange.

6. Railway rail anchoring apparatus, comprising a tie, a bed plate secured to said tie in a position underlying the rail flange, a rectangular opening in said bed plate extending transversely beneath the rail flange, and a spring metal anti-creeper device received in said opening and limiting against the sides thereof, said device including a longitudinally twisted body portion and a turned over end portion forming with said

twisted body portion jaws yieldingly receiving one side edge of the rail flange and exerting a clamping pressure thereon under influence of the twisted spring metal body portion, the turned over end of said device being comprised of spaced prongs sprung apart to resolve the clamping pressure applied to the rail flange into lateral and opposed longitudinal thrusts resisting end-wise movement of the rail in either direction, said prongs further having a generally square shape in cross section, the springing apart of said prongs imparting a set twist thereto presenting corners of the prongs for contact with the rail flange.

7. An anti-creeper device for railway rails, including a length of spring metal angularly shaped in cross section, said length of metal being bent at about its mid portion to form a pair of parallel fingers, the free ends of said fingers being bent back upon themselves in parallel relation to each other, said fingers and said bent over ends forming jaws respectively engageable with the underside and upper side of a rail flange along one edge thereof, said fingers extending along the underside of the rail flange and terminating at their base ends in an upturned lip engageable with the opposite edge of the rail flange, and opposed set twists in the portions forming said jaws to present opposed angle portions engageable with the upper side of the rail flange, an upper angle portion of one jaw and a lower angle portion of the other jaw cooperating to inhibit creep of the rail in one direction and the other corresponding angle portions of said jaws cooperating to inhibit creep of the rail in the opposite direction.
